APPARATUS FOR MARKING SHOE BOTTOMS

William C. Baxter, Beverly, Mass., assignor to
United Shoe Machinery Corporation, Paterson,
N. J., a corporation of New Jersey

Application March 26, 1931, Serial No. 525,488

3 Claims. (Cl. 33—4)

This invention relates to improvements in apparatus for marking shoe bottoms.

In the manufacture of boots and shoes such, for example, as those in which an outsole is secured to a boot or shoe by means of cement, it is desirable to roughen that portion of the upper which overlies the insole on the shoe bottom to insure adhesion between the overlying portion of the upper and the cement. At certain portions of the shoe the curve of the upper merges gradually with the bottom of the shoe, leaving no definite line to indicate the junction of the shoe bottom and the sides of the upper adjacent thereto. The roughing operation ordinarily is performed on the shoe bottom by a skilled operator who must depend upon his eye to determine the limits of the areas to be buffed. If the buffed or roughened area extends beyond the area of the shoe bottom which contacts with the outsole, the appearance of the finished shoe will be damaged because the roughing operation removes the finish on the surfaces on which the operation takes place. On the other hand, if the roughened area does not extend far enough, the crease between the projecting margin of the outsole and the adjacent portion of the upper will not be closed by the sole attaching operation, thereby weakening the attachment of the sole to the upper in the finished shoe.

In view of the foregoing, an object of this invention is to provide an apparatus to serve as an aid in marking shoe bottoms to form a guide line which will define the limits of the area of the shoe bottom to be buffed. In accordance with this object I have provided a novel templet having means for positioning it in proper relation to the shoe bottom. In the illustrated apparatus the templet comprises a body portion which is shaped to coincide with substantially the entire contour of the shoe bottom and is provided at its heel and toe ends with spring clips which engage the upper of the shoe.

During the sole marking operation it is desirable that the shoe be held against movement to prevent slipping of the marking tool and possible displacement of the templet. With this in view the lasted shoe may be held by a support which will engage the shoe upper and hold the shoe securely in position on the support by friction between the upper and the support while the bottom of the shoe is marked. Preferably, and as illustrated, the support has converging side walls forming a cavity or recess in which a lasted shoe is supported in inverted position. The support disclosed herein comprises a cradle having

converging side walls which are covered with a resilient material, such as felt, to prevent injury to the upper of the lasted shoe and to hold the lasted shoe securely in position on the support by friction between the upper and the resilient means.

With the foregoing object in view, the invention will now be described with reference to the accompanying drawings and pointed out in the claims.

In the drawings,

Fig. 1 is a perspective view illustrating the marking of a shoe bottom with the aid of apparatus embodying the present invention;

Fig. 2 is a view in cross section taken along the line II—II of Fig. 1;

Fig. 3 is a detail view of the templet shown in Fig. 1; and

Fig. 4 is a perspective view of a shoe upon which a guide line has been made.

As illustrated herein a base 10 is provided with holes through which screws may be passed to secure the base to a bench or other suitable support. Pivoted secured to the base 10 is a work support or cradle 14 which is reduced at its lower end to form a post 16. The lower end of the post 16 is provided with a bushing 20 into which extends the upper end of a flanged pin 18. The lower end of the pin 18 fits into a hole in the base 10, the flange 19 on the pin fitting into a corresponding recess in the base. The pin 18 and the bushing 20 form a pivot connection between the work support 14 and the base 10 which facilitates operation on a shoe carried by the support. By rotating the support the shoe may be located in a position most convenient for the operator.

The work support or cradle 14 may be made of any stable material such as wood or of metal and may be shaped by molding or by any other suitable process. As best shown in Fig. 2, the walls 23 of the recess 22 converge downwardly to form a cavity or recess 22 which is substantially wedge-shaped in transverse section. This recess is made of such a size that shoes of varying sizes and styles may readily be supported therein. The top of the support 14 is cut away along a re-entrant curve to permit ready access to the shank portions of shoes of different sizes. The walls 23 of the recess 22 are lined with a layer of felt 26 or any other suitable resilient material to prevent injury to the upper of a shoe 24 placed in the recess and also to hold the shoe more rigidly in position because of the friction between the shoe and the felt layer. To insure that the line indicating the location of the edge of the insole

will be properly located, a templet 28 is provided which is shaped to coincide with the contour of the shoe bottom. The templet 28 is made slightly smaller than the shoe bottom to allow for the 5 width of a tool 36 which is drawn around the edge of the templet to mark the line 38 on the shoe bottom. The templet 28 is provided at its heel and toe ends with spring clips 30 and 32 respectively which engage the sides of the shoe 10 upper and locate the templet properly with respect to the shoe bottom. The templet is also provided with a stiffening or reinforcing strip 34 which extends along the shank portion of the templet and insures that the templet 28 will hold 15 its shape to coincide with the contour of the shoe bottom.

As shown in Fig. 1 the shoe 24 on the last 27 is placed bottom side up in the recess 22 and is 20 pressed downwardly into the recess to wedge the shoe against the walls 23. The templet 28 is then placed in position on the shoe bottom with the clips 30 and 32 engaging the shoe upper at its heel and toe ends. Since the portions of the 25 shoe between the clips 30, 32 are wider than the portions which are engaged by the clips, the templet is held against longitudinal displacement and transverse displacement is prevented by the pressure of the clips against opposite sides of the shoe. After the templet has been positioned the 30 operator presses against the templet at the shank and forepart with one hand and with a marking tool 36 in the other hand forms a line 38 on that portion of the upper which overlies the insole. The marking tool may be in the form of a marking wheel, as illustrated, or it may be in the form 35 of a hand-grooving tool which cuts a slight channel in the work.

While it is desirable to form a guide line entirely around the shoe bottom under certain 40 conditions, it may be desirable to mark only at the shank portion of the shoe bottom. The portion of the upper to be marked extends to approximately the edge of the insole which is the same size and shape as the last bottom. The limits 45 of the roughing operation can theoretically be determined by the line which indicates the boundaries of the last bottom. As a practical matter, the line indicating the boundary of the last bottom cannot be determined accurately or with any degree of certainty when an upper has been lasted 50 over the insole. At the forepart of the shoe there is a line indicating the junction of the sides of the shoe with the forepart of the shoe bottom and

a skilled operator may utilize this line with reasonable accuracy as a gage for the roughing operation. At the shank portion of the shoe, however, the curve of the sides of the upper adjacent to the shank portion merges gradually with the shoe bottom making no definite line to indicate the junction of the shank portion of the shoe bottom and the sides of the upper adjacent thereto. It is desirable, therefore, that the shoe bottom be marked at least along the shank portion 10 and this may be accomplished by the use of a templet such as illustrated in Fig. 3, or the templet may extend only to approximately the ball line of the shoe bottom.

Having described my invention, what I claim 15 as new and desire to secure by Letters Patent of the United States is:

1. A templet for use in marking shoe bottoms having a body portion constructed and arranged to coincide substantially with the contour of the 20 shoe bottom, means secured to the shank portion of the templet and constructed and arranged to maintain the shape of the body portion so that it will coincide substantially with the contour of the shoe bottom, and a pair of spring 25 clips secured adjacent to the ends of the body portion of the templet to position the templet on the shoe bottom.

2. A templet for use in marking shoe bottoms having a body portion formed and arranged to 30 conform substantially to the curvature and outline of the shank portion of the insole of a shoe with which the templet is to be used, and means carried by the templet for temporarily securing the templet to the bottom of a lasted shoe where- 35 by the edges of the templet may be used to guide a tool by which the outer boundary of the area to be roughed may be marked on the overlasted margin of the shoe upper.

3. A templet for use in marking shoe bottoms 40 having a body portion formed and arranged to conform substantially to the curvature and outline of the shank portion and forepart of the insole of a shoe with which the templet is to be used, and spring clips carried by the templet and 45 constructed and arranged temporarily to secure the templet to the bottom of a lasted shoe whereby the edges of the templet will be correctly positioned to guide a tool by which the outer boundary of the area to be roughed may be 50 marked on the overlasted margin of the shoe upper.

WILLIAM C. BAXTER.
